UNITED STATES PATENT OFFICE.

WILLARD H. BUNDY, OF SYRACUSE, NEW YORK, ASSIGNOR TO W. H. BUNDY RECORDING COMPANY, OF SYRACUSE, NEW YORK, A CORPORATION OF NEW YORK.

TIME-RECORDER.

1,213,662.

Specification of Letters Patent.

Patented Jan. 23, 1917.

Application filed July 2, 1912. Serial No. 707,161.

To all whom it may concern:

Be it known that I, WILLARD H. BUNDY, of Syracuse, in the county of Onondaga and State of New York, have invented a certain 5 new and useful Time-Recorder, of which the following is a specification.

This invention relates to time recorders, and particularly to means for positioning the shiftable parts thereof and for controlling the printing operation in any position 10 of such shiftable parts; and the invention consists in the combinations and constructions hereinafter set forth and claimed.

In describing this invention reference is 15 had to the accompanying drawing in which like characters designate corresponding parts in all the views.

Figure 1 is a front elevation of a time recorder embodying my invention, parts being removed. Fig. 2 is a vertical sectional view of parts shown in Fig. 1, parts being removed. Fig. 3 is an inner face view of one 20 of the side plates and contiguous parts. Fig. 4 is an isometric view of the card receiver 25 shifting means and contiguous parts.

1 is the frame of the time recorder, the frame comprising side plates 2, 3 connected by suitable cross rods 4.

5 is the carriage of the time stamp or impression making mechanism which carries a 30 suitable printing element, as type wheels, which are connected by means of a shaft 6 to a time movement. The carriage is supported by the cross bars 4.

35 7 is a card receiver arranged to support the card 8 in position to receive the impression from the time stamp. One of the elements 5, 7 here shown as the card receiver, is shiftable relatively to the other, as the carriage 5, to position the records in different columns transversely of the card. As seen in Figs. 1 and 2, the card receiver is arranged in vertical position and has its mouth 9 for the card at its upper end, and 40

45 is movable laterally, it being formed with eyes 10, Figs. 1 and 2, which slide along guide rods 11 supported by the side plates 2, 3.

The means for shifting the card receiver 7

usually comprises a hand operated rock shaft 50 12, Figs. 1 and 4, extending forwardly and rearwardly relatively to the frame, and a toothed segment 13 mounted on the rock shaft and meshing with a rack 14 extending laterally from the card receiver. The rock 55 shaft is supported in bearings 15 projecting from the outer face of the side plate 2.

The rock shaft is impositively locked in order to hold the card receiver in any one of the positions it is capable of assuming, 60 by means comprising a segment 16, Fig. 4, mounted on the rock shaft 12 and having notches 17 corresponding in number to the number of positions capable of being assumed by the card receiver, said notches being formed with inclined sides as 18 with which a pivoted spring-pressed detent 19 coacts, the inclined sides serving to force the detent out of operative position when rotative force is applied to the rock shaft. 70

20 is an abutment or stop, Figs. 1 and 2, for the card 8 in the receiver 7.

21 is a carriage slideable in ways in the card receiver and supporting the abutment, such abutment being movable in a direction 75 at an angle to the shifting movement of the receiver, that is, vertical, in this embodiment of my invention.

The abutment carriage 21 is shifted in the card receiver periodically, preferably by 80 means actuated by the time movement but may be operated by hand. In either case the means for actuating the card abutment includes a rocking element as a yoke 22 supported by the frame between the side plates 85 2, 3, and a cam 23 for actuating the yoke, the yoke including rock arms 24 connected at their ends by a rod 25, which rod is connected to the central part of the abutment carriage by a link 26, the link being slidably 90 engaged with the rod 25 to accommodate the shifting movement of the card receiver.

28 is an elongated rocking element or wing carried by the carriage 21 in position to be operated by the movement of the abutment 95 20.

29 is an elongated rocking element or wing fixed from movement with the carriage

21, and here shown as having spindles 30
jounaled in bearings formed in inwardly
extending arms 31 carried by the side plate
3 one above the other, one of the spindles
5 30, as the lower spindle carrying a rock arm
32 which is connected by means of a link
33 to a latch lever 34 pivoted to the frame
and having one end normally arranged in
the path of the operating lever 35 for the
movable platen or hammer 36.

10 The hammer or platen 36 is mounted on a
rock shaft 37 journaled in the frame and
provided with a shoulder 38, with which co-
acts a pivoted latch 39 carried by the lever
15 35, said latch being moved out of engage-
ment with the shoulder 38 by a knock-off
device 40 also carried by an arm on the rock
shaft 37.

The movement of the lever downwardly
20 is against the action of a suitable spring, and
such downward movement tensions a spring
41 acting on a rock arm 37 on the rock
shaft 37 on the outside of the side plate 3,
the spring actuating the rock shaft 37 and
25 hammer 36 when the device 40 knocks off
the latch 39.

When the card is inserted in the receiver
7 it depresses the abutment 20, rocking the
wing 28 upwardly which transmits its mo-
30 tion to the wing 29, rocking the spindles 30
of said wing, actuating the arm 31 and with-
drawing the latch 34 out of the path of the
operating lever 35.

Owing to the use and arrangement of the
35 wings 28, 29, the wing 29 will be operated
in whatever transverse position the card re-
ceiver is placed and in whatever position
the abutment carriage happens to be.

As here shown, the wing 28 is provided
40 with an arm 42 between its ends which slid-
ably engages a depending shoulder 43 ar-
ranged centrally of the abutment, and the
abutment is connected to its carriage by
means of pin-and-slots 44 located near op-
45 posite ends of the abutment; and spring
arms 45 act upwardly on opposite ends
of the abutment. Thus when either end
of the abutment is depressed, the abut-
ment moves about the pin-and-slot connec-
50 tion at the other end as a center, and thus
the central shoulder 43 is but slightly de-
pressed and partially actuates the wing 28;
and hence in order to fully actuate the wing
28 both ends of the abutment 20 must be
55 depressed simultaneously. When but one
end of the abutment 20 is depressed, the
latch 34 is but slightly displaced, and in
order that the lever 35 may still be locked,
the latch is provided with two shoulders 46,
60 one of which is normally engaged with said
lever and the other of which moves into the
path of the lever when but one end of the
card abutment 20 is depressed.

The time recorder is also provided with
65 means for gripping the card 8 when in the

receiver 7 and preventing the shifting of
the card in the receiver 7 when the operat-
ing lever 35 has been but partly actuated
after being unlocked by the movement of
the card abutment 20 by the card as de-
scribed.

48 is a gripping member here shown as
a sliding part movable through an opening
49 in the front wall of the mouth of the re-
ceiver, and carried by the rail 50 formed
75 with the eyes 10 and to which the rack 14
is secured.

51 is a rock shaft extending in front of
the card receiver transversely thereof and
supported by ears 51^a on the side plates 2, 3,
30 the shaft having eccentric means as an elon-
gated wing 52 arranged to press against a
shoulder 53 on the gripping member 48 dur-
ing rocking of the shaft, the wing 52 being
long enough to engage the shoulder in all
85 positions of the card receiver. The rock
shaft is connected to the operating lever 35
to be actuated thereby in any suitable man-
ner, as by an angle or bell crank lever 54
pivoted to the inner face of the side plate 3
90 and having one arm thereof coacting with
an arm 55 on the rock shaft 51 and its other
arm connected by a link 56 to the lever 35,
Fig. 3.

What I claim is:

1. In a time recorder, impression mak-
ing mechanism including a handle for op-
erating said mechanism to make a record, a
shiftable card receiver, a card stop for lim-
iting the movement of the card into the re-
ceiver, a device for clamping the body of
the card against a stationary part after the
card engages said stop, and mechanism ac-
tuated by the handle for operating said de-
vice, substantially as and for the purpose set
forth.

2. In a time recorder, a laterally shift-
able card receiver, a card abutment, an abut-
ment carriage movable periodically in the
card receiver at an angle to the shifting
110 movement thereof, the abutment being mov-
able relatively to the carriage by the card
when inserted in the receiver, printing mech-
anism including a movable platen, an op-
erating lever for moving the platen, means
115 for normally locking the operating lever
from movement, and means for operating
the locking means, the lock operating means
being arranged to be operated by the card
abutment in any position of the card re-
ceiver or the abutment, substantially as and
for the purpose described.

3. In a time recorder, a frame for sup-
porting type wheels, a platen, a lever for
operating the platen, a lock for the lever,
a laterally shiftable card receiver, a card
abutment movable in the card receiver, an
elongated rocking part movable as a unit
with the abutment and being movable about
its axis by the abutment when the abutment
130

is engaged by the card, and a second elongated rocking part fixed from movement with the abutment and extending crosswise of the first-mentioned rocking part, and 5 means operated by the second-mentioned rocking part for releasing the lock for said lever, substantially as and for the purpose specified.

4. In a time recorder, a shiftable card receiver, a card abutment in the receiver, a carriage for the abutment movable in a direction at an angle to the shifting movement of the receiver, printing mechanism including a movable platen, means for actuating the platen, means for normally preventing the operation of the actuating means comprising an elongated rocking element carried by the abutment carriage and extending transversely of the card receiver, 15 a second elongated rocking element fixed from movement with the carriage and extending at an angle to the first-mentioned rocking element in position to be engaged and actuated thereby in all positions of the card receiver and the movable abutment carriage, and a latch for locking the operating means, the latch being operated by the second-mentioned rocking element, substantially as and for the purpose set forth.

5. In a time recorder, a frame including side plates, one side plate having inwardly extending arms, a time stamp supported by the frame and carried between the side plates, a movable platen coacting with the time stamp, a card receiver arranged between the platen and the time stamp, and shiftable laterally into a plurality of positions, a movable card abutment in the receiver, a carriage for the abutment movable 20 in a direction at a right angle to the shifting movement of the receiver, means for actuating the platen, means for preventing the operation of the actuating means comprising an elongated rocking element carried by the abutment carriage and extending transversely of the card receiver, a second elongated rocking element supported by the inwardly extending arms of the frame, and extending at an angle to the first-25 mentioned rocking element in position to be engaged and actuated thereby in all positions of the receiver and the movable abutment carriage, and a latch supported by the frame and coacting with the operating means, the latch being connected to the second-mentioned rocking element, substantially as and for the purpose described.

6. In a time recorder, a shiftable card receiver, a card stop in the receiver, a 30 card abutment movable in the receiver after the card is engaged with the stop, the grip coacting with a stationary part in a direction at an angle to the shifting movement of the receiver, a carriage for the abutment, means for actuating the abut-

ment comprising a rocking element, a link connecting the rocking element and the carriage, the link being connected centrally to the carriage and being slidably engaged with the rocking element to slide along 70 the same during the shifting of the card receiver, substantially as and for the purpose specified.

7. In a time recorder, impression making means including an operating handle, a 75 shiftable card receiver, a card grip for engaging the card when the card is in the receiver, means for actuating the card grip including a part coacting with the grip to actuate the same in engagement with the 80 card in any position of the card receiver, and means for actuating said part upon the operation of said operating handle to make an impression, substantially as and for the purpose set forth.

8. In a time recorder, a shiftable card receiver, a card abutment, an abutment carriage movable periodically in the card receiver at an angle to the shifting movement thereof, the abutment being also movable 90 relatively to the carriage by the card when inserted in the receiver, printing mechanism including a movable platen, an operating lever for moving the platen, means for normally locking the operating lever from movement, 95 means for operating the locking means, the lock operating means being arranged to be operated by the card abutment in any position of the card receiver or the abutment, a card grip for holding the card from movement in the receiver when the card is engaged with the abutment, and means for operating the grip in any position of the card receiver, said means being connected to the operating lever, substantially as and 100 for the purpose described.

9. In a time recorder, a shiftable card receiver, a card abutment in the receiver, a carriage for the abutment movable in a direction at a right angle to the shifting movement of the receiver, printing mechanism including a movable platen, means for actuating the platen, means for preventing the operation of the actuating means comprising an elongated rocking element carried by the abutment carriage and extending parallel to the direction of movement of the card receiver, a second elongated rocking element fixed from movement with the carriage and extending at a right angle to the first-mentioned rocking element into 110 position to be engaged and actuated thereby in all positions of the card receiver and the movable abutment carriage, a latch for locking the operating means, the latch being operated by the second-mentioned rocking element, a card grip for engaging the card in the receiver, means for operating the grip including a rock shaft extending 120 parallel to the direction of movement of the 115 125 130

card receiver, and having an elongated part for engaging the grip, and connections between the rock shaft and the operating means, substantially as and for the purpose specified.

In testimony whereof, I have hereunto signed my name in the presence of two at-

testing witnesses, at Syracuse, in the county of Onondaga, in the State of New York, this 25th day of June, 1912.

WILLARD H. BUNDY.
